UNITED STATES PATENT OFFICE.

ALBERT KALINOSKY, OF NEW YORK, N. Y.

PHONOGRAPH REPEATER.

Application filed January 23, 1923. Serial No. 614,429.

To all whom it may concern:

Be it known that I, ALBERT KALINOSKY, a citizen of Poland, residing at New York, county of New York and State of New York, have invented certain new and useful Improvements in Phonograph Repeaters, of which the following is a specification.

My invention relates to improvements in the repeating mechanism of phonographs, 10 and it is the principal object of my invention to provide a mechanical repeating mechanism which is automatic in its operation, and which may conveniently be installed into any existing type of musical 15 instruments of this class.

Another object of my invention is the provision of a repeating mechanism allowing an adjustment to cause the operation of the repeating mechanism to suit the exact 20 size of each record to be reproduced.

A further object of my invention is the provision of a repeating mechanism providing for the raising of the reproducer needle from the record groove prior to the return 25 of the reproducer to starting position.

A still further object of my invention is the provision of a repeating mechanism including means for regulating the gradual introduction of the needle into the record 30 groove at the completion of the return movement in order to avoid injury to the record.

Other objects of my invention are the provisions of means for adjusting the repeating mechanism to suit the width of the 35 inner circle or to the size of the groove nest, and of means for throwing the repeating mechanism out of action if this should be desired.

Still further objects of my invention are 40 the provision of means for coupling the repeating mechanism with the motor and uncoupling it therefrom at given times, and of means for ensuring this action at the proper times.

According to my invention the record itself is used for returning the repeating mechanism into its working position after 45 each operation.

The invention shall now be described in 50 its preferred form with reference to an embodiment thereof in a machine using disk records, and which is provided with the usual articulated reproducer arm.

In the accompanying drawings forming 55 a material part of this disclosure:

Figure 1 is a front view of a phonograph

of a conventional type equipped with the repeating mechanism according to the present invention.

Figure 2 is a top plan view seen along line 2—2 of Figure 1.

Figure 3 is a top plan view on an enlarged scale, after removal of the closing plate covering the repeater mechanism.

Figure 4 is a fragmentary top plan view 65 after removal of the closing plate and the upper part of the tone arm.

Figure 5 is a side view, partly in section of the interior mechanism of the phonograph and the tone-arm in longitudinal sec- 70 tion.

Figure 6 is a top plan view of the tone-arm in longitudinal section on line 6—6 of Figure 5.

Figure 7 is a top plan view of the worm 75 shaft and co-operating parts.

Figure 8 is a longitudinal section through the worm shaft on line 8—8 of Figure 7.

Figure 9 is an edge view of a locking element for a shaft coupler. 80

Figure 10 is a bottom plan view of this element.

Fig. 10^a is a broken perspective view showing the cooperation of the locking element and latch. 85

Figure 11 is a front elevation of the lower part of the tone-arm with the operating finger and means for regulating its position.

Figure 12 is a side view thereof. 90

Figure 13 is a fragmentary top plan view of the shaft coupling mechanism.

Figure 14 is a longitudinal section through the mechanism illustrated in Figure 13 on line 14—14 of Figure 13. 95

Figure 15 is a top plan view of a locking latch.

Figure 16 is an edge view thereof.

Figure 17 is a front view of the repeating mechanism looking in the direction 100 of line 17—17, Figure 4.

Figure 18 is a side elevation of the parts shown in Figure 17 partly in section on line 18—18 of Figure 17.

Referring more specifically to the drawings, 10 indicates the ordinary box or housing of the phonograph provided with a cover 11 hingedly connected in the ordinary manner, 12 the turn table and 13 a disk record.

The usual amplifier and bracket 14 support the articulated reproducer arm 15 pivotally attached by means of pin 16 to

one arm of a bracket 17, secured with its other arm to the upper part of the box 10.

The free end of the tone-arm 15 is shaped to form a drum 18 open at the ends and the front. In this drum the roof bar of a hollow T-piece 19 is rotatably arranged, the outer ends of which carry handles 20 and 21 while its inner wall are connected by means of pins 22 and 23. The tubular shaft of the T-piece is open at its end and adapted to receive a knee piece 24 to which the sound box 25 carrying the stylus 26 is removably attached in the usual well known manner.

To pin 23 is attached a longitudinal rod 27 near its inner end, while the end of said rod loosely engages the other pin 22. A wire loop 28 is attached with one of its ends to the inner wall of the tone arm and rests with its looped other end 29 on rod 27, to the free end of which a chain 30 is attached at one end, the other end of which is secured to one end of a curved bar 31 attached with its opposite end to a pin 32 rotatably secured in the walls of bracket 14 extending through these walls and carrying at one end a curved finger 33. The end of arm 15 has at its lower end a transverse partition wall 34 to which a pin 35 is attached, adapted to enter into an opening in a partition 36 arranged within bracket 14.

In the outer wall of arm 15, at some distance above its lower end two screws 37 and 38 are secured, and a curved plate 39 provided with longitudinal slots 40, 41 slides across the outer wall of the tone arm and is guided by the shafts of screws 37 and 38 playing in slots 40 and 41. At one end the plate 39 carries two outstanding checks 42 and 43 (Fig. 4) and the lower flattened end 40 of an angular lever 44 is engaged between both cheeks, while its upper end is guided through a bracket 45 and shaped into a handle 46 by means of which plate 39 can be displaced across the tone arm.

Plate 39 is formed in approximately its center with an angular nose or projection 47 having a toothed or stepped outer end 48, and to the projection 47 is pivotally secured by a pin 49 with a binding effect the split rear end of a finger 50, to the upper front edge of which one end of a leaf spring 51 is attached as at 52, the other end of which is curved upwardly and then downwardly to pass through a slot in finger 50 into engagement with the steps or teeth 48. The side wall of finger 50 is cut to form a curved groove 53, and the other end of finger 50 is forked to form two prongs 54 and 55, and a hook 56 is attached to the side face of finger 50 opposite the groove 53.

A shaft 57 journaled in the box 10 is adapted to receive its rotation by means of pulley 58 from the pulley 60 on a shaft 61 rotated by the motor of the phonograph in the usual manner. This shaft carries a col-

lar 62 at its inner end which is hollow to receive the end 63 of a connecting member 64 having a collar 65 at one end and a collar 66 at its opposite end which is also hollow for the reception of the end of a worm shaft 67 keyed to member 64 as at 68. The member 64 and the end of shaft 57 are provided with a longitudinally extending channel 69, in which a latch 70 is longitudinally displaceable provided with a recess 71 in its upper face, the end of which latch is engaged by a spring 72 normally tending to press the latch into its locking position.

A coupling element or leaf spring 73 is fastened at its rear end to a block in box 10 as at 74, while its other end is formed into a lug 75 having an upstanding lip 76 at one side. The lug 75 is split as at 77 in its lower face and cut away as at 78, and the material of lug and lip 76 is set off so as to form a channel 79 of a curvature best illustrated in Figure 8.

Collars 65 and 66 are channeled to guide a pin or rod 80, the outer end of which is formed into an open loop, and the inner pointed end of which engages in the channel of lug 75 to raise the same while gliding along the upper curved wall of the channel 79 to raise the lower, downwardly curved lip 81 out of recess 71 of latch 70 to allow a shooting home of latch 70 under the action of spring 72 to couple shaft 57 with member 64 to which the worm shaft 67 is keyed (see Fig. 14).

A hair spring 82 is attached at one end to collar 66 and its opposite end is wound around the shorter shank of pin 80, and this spring has the tendency to return pin 80 after each operation into its original position as will be hereafter more fully described.

Collar 66 carries an S-shaped pin 83 for a purpose later to be referred to, and worm shaft 67 carries at its opposite end a collar 84 provided with an upstanding ridge 85.

A tubular sleeve 86 has formed therewith a cam 87 and is keyed as at 88 to a stub shaft 89 which is also keyed as at 90 to worm shaft 67, and the other end of which is journaled in a suitable bearing 91 in box 10.

The cam 87 is eccentrically mounted on shaft 89 and has a shape best illustrated in Figure 5, in which the upper end of the cam is formed into a curved thumb piece 92 separated from the cam by a recess 93, and finger 33 engages cam 87 as shown in Figure 5.

A block 94 having a longitudinal slot 95 and a graduation 96 is secured to the top plate 97 of the phonograph box 10 which is also slotted in alignment with slot 95 to allow the passage of a vertical pin 98 provided at its upper end with a handle 99 by means of which pin 98 may be displaced in slot 95. This pin is also passed

through a horizontal bar 100 carrying at its other end an operating knob 101. The lower end of pin 98 is secured to a horizontal bar 102 having an angular arm 103 extending across worm shaft 67 above the same, and ending into an angular finger 104. Bar 100 is displaceable in a depression of cover or top plate 97, and a cover plate 106 set into plate 97 flush with its upper face, covers the repeating mechanism, and is provided with guides on its upper face in which a segmental slide 107 is displaceable to allow an inspection of the mechanism through a slot in plate 106 covered by said slide 107.

Means are provided for shifting block latch 70 to disconnect the worm shaft 67 from the shaft 57, by means of lug 75 which is formed on one end of leaf spring 73, the under side of said lug 75 having a cam 78 as is shown clearly in Figs. 9 and 10; and said leaf spring is so mounted at 74 to create a pressure between the underside of cam face 78 and upper face key 70, thereby keeping under side of cam face 78 in contact with upper face of key 70 when worm shaft 67 and shaft 57 are connected; and as the two rotate together with key 70, which has a recess 71, one side of said recess 71 having a beveled side 70^a (see Fig. 15) comes in contact with cam face 78 hereby allowing the narrow portion 76^a of cam face 78 to gradually drop into recess 71 and disengage key 70 from shaft 57.

As will be apparent from the following description of the operation, the projection 104 at the end of the arm 103 is, in the revolution of the worm shaft 67, engaged by the ridge 85 and moved upwardly to lift the arm 103. This arm in its upward movement engages beneath hook 56 of finger 50, to lift the finger and disengage the same from the worm shaft to interrupt the swinging movement of the tone arm. Therefore, the position of the arm 103 determines the point at which the swinging movement of the tone arm is arrested, and as this arm 103 can be moved to different positions by shifting the bar 102 by means of the handle 99, it is obvious that the outward movement of the tone arm can be interrupted at any desired position, that is, in accordance with the initial or starting groove of the record. By this construction, the tone arm can be placed in proper starting position for records of different sizes through the adjustment of the bar 102 as described.

The repeating mechanism operates in the following manner:

After adjusting slide loop 102, 103, 104 by the proper manipulation of knob 101 or handle 99 to suit the size of the record to be played, and shifting finger 50 by the proper manipulation of handle 46 according to the size of the inner circle of the record, so that it will engage needle 80 at the

proper moment, i. e. at the end of the record, the motor is started. The engagement of the needle 26 with the record 13 will swing the arm 15 in the usual manner to turn in bracket 14, until, at a predetermined point i. e. at the end of the record, the prongs 54 and 55 of finger 50 will have engaged needle 80 and press the same inwardly until its pointed end gliding along the inner upper curved wall of slot 79 will lift leaf spring 73 to allow latch 70 to be shot home under the action of its spring 72 to couple shaft 57 with the worm shaft 67.

At this moment, when worm shaft 67 starts to rotate, the S-shaped pin 83 on collar 66 will engage and ride upwardly in groove 53 of the finger 50 along the bottom wall thereof and bring the same into engagement with the worm shaft. At this moment the finger 33 will travel towards the highest point of the cam 87 and during this motion finger 33 will be swung backward to draw the inner end of curved bar 31 forward and lower its rear end, tautening chain 30 and pulling on lever 27 to rotate the T-piece 19 within drum 18 and raise its outer end to which the sound box is attached so that the same is lifted off the record. The rotation of worm shaft 67 with which finger 50 is engaged will return finger and tone arm or horn 15 into its original position, and at this time ridge 85 will engage arm 104 and lift the same to engage hook 56 of finger 50 and lift the latter off the worm shaft. During this operation the cam 87 rotating with worm shaft 67 will be in a position which allows finger 33 to drop into the lowest part, so that bar 31 is raised again to slacken chain 30 and to allow the needle 26 to drop into engagement with the record and to repeat the above described cycle of movements.

Having thus described my invention what I claim as new and desire to secure by Letters Patent of the United States is:

1. A repeating mechanism for phonographs including a reproducer, a tone-arm, and an operating support for a record, an operating finger carried by said tone-arm, a motor driven shaft, a worm shaft, means for coupling both shafts adapted to be operated by said finger at the end of a record, means for engaging said finger with said worm shaft to return the finger and tone-arm to their original positions, means for lifting and lowering said reproducer out of and into engagement with a record.

2. A repeating mechanism for phonographs including a reproducer, and a tone-arm comprising an operating finger carried by said tone-arm, a motor driven shaft, a worm shaft, a cam carried by said worm shaft, means for coupling said shafts by the operation of said operating finger at the end of a record, means for engaging said operat-

- ing finger with said worm shaft to return said tone arm and finger to starting position, means actuated by said cam for lifting said reproducer from a record at the end of the 5 sound groove in the same, and for lowering the needle of said reproducer against the record upon the arrival of said tone-arm and operating finger at their original position.
3. In a repeating mechanism for phonographs including a reproducer, a tone-arm, and an operating support for a record, an operating finger on said tone-arm, a motor driven shaft, a worm shaft, a spring controlled latch for coupling said shafts, a 10 means for normally holding said latch in its inoperative position, a needle adapted to be engaged by said operating finger at the end of a record for releasing said latch holding means to allow a coupling of said shafts by 15 said latch, a means for pressing said operating finger after the operation of said needle into engagement with said worm shaft to return said finger and tone-arm into their original starting position, a cam on said 20 worm shaft for actuating said reproducer lifting and lowering means at the end and the beginning of a record to allow the returning of said tone-arm into its original position.
- 30 4. In a repeating mechanism for phonographs including a tone-arm and reproducer, a cam operated means for lifting and lowering said tone-arm, comprising a drum at the end of said tone-arm, a hollow T-piece rotatably secured in said drum adapted to receive the reproducer socket, a pair of pins in said T-piece, a longitudinal bar pivotally attached to one of said pins, a chain attached to the opposite end of said bar, a curved 35 finger adapted to be operated by said cam, a curved bar adapted to be rotated by said finger to which the free end of said chain is attached adapted to tighten and slacken said chain upon the operation of said cam to lift 40 and lower said T-piece and reproducer attached thereto, and a wire loop adapted to be secured at one end in said tone-arm and to engage with its other looped end said longitudinal bar.
- 45 5. In a repeating mechanism for phonographs including a tone-arm, an operating finger on said tone-arm, and means for securing said finger to said tone-arm comprising a longitudinally slotted plate, screws passed 50 through the slots in said plate for slidably guiding said plate, a boss on said plate, a finger pivotally secured at its rear end with a binding action to said boss, a pair of prongs at the front end of said finger, a plurality of steps or teeth at the front end of 55 said boss, a spring secured at one end to the top edge of said finger and engaging with its lower end the steps of said boss, a curved groove in one side of said finger adapted to be engaged by means for depressing said 60 finger, and a hook at the opposite side of said finger adapted to be engaged by means for lifting said finger, and means for shifting said plate and finger transversally across said tone-arm.
6. In a repeating mechanism for phonographs including a longitudinally recessed motor driven shaft, and a worm shaft, comprising means for coupling both shafts for actuating said repeating mechanism, a collar 70 on said motor driven shaft, a longitudinally recessed connecting piece around one end of which said motor driven shaft revolves having its other end keyed to said worm shaft, a recessed latch within the longitudinal recesses of said motor driven shaft and said connecting piece, a spring for normally pressing said latch into locking position, a leaf spring having a projection at its front end normally pressed into engagement with the recess in said latch, and means for engaging said leaf spring to lift its projection out of the recess of said latch for allowing a shooting of said latch into position to couple said motor driven shaft and said connecting 80 piece and worm shaft.
7. In a repeating mechanism for phonographs, a recessed motor driven shaft, a worm shaft, a recessed connecting piece secured at one end to said worm shaft and 90 allowing a revolving of said motor driven shaft around its opposite end, a recessed spring controlled latch, a leaf spring secured at one end to the phonograph, a lug at its opposite end adapted to normally engage the recess in said latch to hold the same in its uncoupling position, said lug having a slanting and curved bore, perforated collars on said connecting piece and said worm shaft, a needle guided in the perforation in said collars having a pointed end engaging the upper wall of the bore of said lug and adapted to be operated to lift said lug out of engagement with the recess in said latch for allowing a coupling of said 100 shafts by the latch projected into coupling position by its spring.
8. In a repeating mechanism for phonographs including a tone-arm, an operating finger, a guide for attaching and guiding said finger on said tone-arm, a means for slidably displacing said guide and finger by hand, a motor driven shaft, and a worm shaft, means for coupling both shafts at a given time, a means for normally keeping said coupling means inoperative, a needle adapted to be engaged by said finger to lift said means keeping said coupling means inoperative to allow a coupling of said shafts by said coupling means for allowing a 110 rotation of said worm shaft, a spring for returning said needle into inoperative position after each operation by said finger, said finger having a lateral curved channel, a collar on said worm shaft, an S-hook on 115
- 120
- 125
- 130

- 5 said collar adapted to engage the channel wall of said finger to depress the same upon said worm shaft during its rotation for guiding finger and tone-arm into their original position, and means on said finger for lifting the same out of engagement with said worm shaft and allow a return into its needle operating position by said tone-arm during the play of a record.
- 10 9. The combination with a phonograph having a rotatable record carrier for supporting a record in disk form having a zone of grooves, and a tone-arm having a sound reproducing stylus, of a cam and shaft therefor and an operating finger on said tone-arm, normally inoperative for effecting a coupling of said cam shaft to the motor shaft of the phonograph upon the completion of the playing of the record, cam actuated means for automatically lifting the stylus off the record on the coupling of said shafts, a worm on said cam shaft, means for depressing said finger, after its coupling operation into engagement with said worm
- 15 for returning finger and tone-arm into their original position, said cam actuated means being also arranged for automatically lowering the stylus onto the record upon the arrival of said finger and tone-arm in their original position. 25
- 20 10. In a repeating mechanism for phonographs including a tone-arm and a reproducer, an operating finger adjustably attached to said tone-arm, a hook on one side of said finger, means for operating said finger and thereby the tone arm to move the tone arm to a starting position, a sliding frame adapted to engage said hook for disconnecting said finger from said operating means at a predetermined point in the movement of said finger and tone arm, and manually operable means for adjusting said sliding frame to ensure the lifting of said finger at the proper moment in accordance with the size of a record. 30 35 40 45

In testimony whereof I have affixed my signature.

ALBERT KALINOSKY.
